H. M. SHEER.

HEATING SYSTEM FOR BROODERS, INCUBATORS, AND THE LIKE.

APPLICATION FILED DEC. 17, 1921.

1,432,576.

Patented Oct. 17, 1922.

UNITED STATES PATENT OFFICE.

HENRY M. SHEER, OF QUINCY, ILLINOIS.

HEATING SYSTEM FOR BROODERS, INCUBATORS, AND THE LIKE.

Application filed December 17, 1921. Serial No. 523,080.

To all whom it may concern:

Be it known that I, HENRY M. SHEER, a citizen of the United States, residing at Quincy, in the county of Adams and State of Illinois, have invented certain new and useful Improvements in Heating Systems for Brooders, Incubators, and the like, of which the following is a specification.

My invention relates to an improvement 10 in heating systems for brooders, incubators, and the like, the present invention being of the nature of, but an improvement on, the invention set forth in my applications Ser. Nos. 451388, filed in the Patent Office March 15 10, 1921, and 467722, filed May 7, 1921.

What I want to cover in this present application is a combination by which the oil level carried by the float, and the oil level carried by the bottle are so nearly 20 coincident that the burner cannot flood or overflow in the event of the float mechanism getting out of order.

In my previous constructions, and also in every float construction hitherto patented, 25 the oil level as determined by the bottle is always considerably higher than the overflow point of the burner, so that, in case the float valve should fail to function, the oil would flood the burner, unless an overflow was provided at the float chamber.

In the above-mentioned applications, there is a vent hole in the float chamber, which 35 also serves as an overflow in case the float valve should fail to shut off the oil. The vent hole referred to, is absolutely necessary, for if the float chamber is not vented, the air could not escape, hence the oil would never rise far enough to close the float valve. The vent, therefore, serves a double 40 purpose, but what I have accomplished in the present invention is the prevention of all possibility of the oil overflowing at any point.

The construction, and arrangement of the 45 float, ball-valve, etc., are substantially the same as in my previous applications, but the opening in the center of the float is enlarged, for the reasons that will appear hereinafter.

The accompanying drawing is a vertical 50 sectional view.

A, is the usual oil bottle; B, is the metal oil chamber; C, is a diaphragm dividing the oil chamber into upper and lower compartments; D, is a vent for the lower compartment; E, is a pressed metal cup to re-

ceive the neck of the oil bottle A. This cup extends through an opening 1 formed therefor in the center of the diaphragm. The cup has a crimped upper edge 2, which rests 60 removably upon the diaphragm.

F, indicates a fine screen or strainer located within the cup; and G, is a baffle-plate upon which the strainer is supported. This baffle-plate rests centrally on the bot- 65 tom of the cup, and has the function of pressing back the bottle-valve 3 to permit the oil to escape from the bottle.

H, represents the float; I, a plate covering the opening 5 in the center of the float, 70 this plate being provided with holes 6 to permit the oil to pass freely therethrough.

J, is the ball-valve, which may either be fastened to the plate I or permitted to rest in valve-seat 4 as illustrated in the drawing. 75

The seat 4 for the ball J in the bottom of the cup E may be pressed in the sheet-metal. Every economy in space must be taken care of in order to bring the neck of the bottle as near as possible to the oil level carried 80 by the float, as indicated by the line L. The oil level as carried by the bottle is indicated by the line K just slightly above.

In operation, the depth of oil in the bottom of the oil groove of the burner 8 is 85 hardly one-sixteenth of an inch when carrying full volume. The depth of the oil groove of the burner is usually five-eighths. In most types of burners, the oil groove is considerably deeper than this. 90

In view of the oil groove in the burner, and the depth of the oil at the operating point, it will be clearly seen that the oil could not overflow at the burner even if the float failed to function. While the heater 95 is in operation, the burner of course will take care of any slight leakage of oil at the ball-valve, or in other words, the burner will always use more oil than could possibly leak past the ball-valve, providing it is not 100 prevented from seating. This slight leakage, however, would in course of time flood the burner or cause the oil to overflow at some other point after the flame is extinguished. 105

Such a condition is more or less objectionable. With my present construction, the chamber or cup E receiving the oil from the bottle is drawn out of a single piece, hence there is no possibility of a leakage except 110 at the valve seat 4 of the ball valve J.

The gauze screen F will prevent any

coarse dirt from getting into the ball-valve, and as the cup E can be lifted out, it affords every opportunity to keep these parts perfectly clean. Since the oil level is within 5 the cup E, the diaphragm need not be soldered tight in the oil-chamber C, in fact arrangement can be provided by means of which the diaphragm C could be lifted out, and the entire float removed. Ordinarily 10 there is no occasion for this, however, since the only parts that will ever need attention are the screen F, and the valve-seat 4 for the ball valve J.

The baffle-plate G is for the purpose of 15 supporting the screen F, and also for the purpose of supporting the bottle-valve 3. When this valve is open, the oil flows through the screen F, through openings 9 in the baffle-plate.

20 The entire structure may be raised and lowered through the screw 10 and the nut 11, and locked with a key 12.

The manner of applying this new construction to the balance of the heater may 25 be the same as in my other application.

I claim:

1. The combination with an oil supply and a comparatively shallow oil chamber forming a seat for the support thereof, of 30 a float in the oil chamber approximately on a level with the outlet from the oil supply, whereby the oil level carried by the float and oil supply chambers are approximately coincident.

35 2. The combination with an oil supply and a comparatively shallow oil chamber forming a seat for the support thereof, of a float in the oil chamber approximately on a level with the outlet from the oil supply, 40 whereby the oil level carried by the float and oil supply chambers are approximately coincident, and a ball valve carried by the float for controlling the passage of oil from the oil supply to the oil chamber.

45 3. The combination with an oil supply chamber, an oil chamber having a diaphragm thereacross, whereby it is divided into two compartments having an opening therethrough, a cup extending down through 50 said opening, and receiving therein the outlet of the oil supply, and having a valve-seat therein, of a float approximately in the plane of the outlet from the oil supply, the float carrying a valve for controlling 55 the valve-seat outlet of the cup.

4. The combination with an oil supply chamber, an oil chamber having a diaphragm thereacross, whereby it is divided into two compartments having an opening therethrough, a cup extending down through 60 said opening, and receiving therein the outlet of the oil supply, and having a valve-seat therein, of a float approximately in the plane of the outlet from the oil supply, the float carrying a valve for controlling the 65 valve-seat outlet of the cup, the cup removably supported upon the diaphragm and in the opening therethrough.

5. The combination with an oil supply chamber, an oil chamber having a diaphragm thereacross, whereby it is divided into two compartments having an opening 70 therethrough, a cup extending down through said opening, and receiving therein the outlet of the oil supply and having a valve-seat therein, of a float approximately in the plane of the outlet from the oil supply, the float carrying a valve for controlling the valve-seat outlet of the cup, the float having a recessed center into which the cup extends, and having an opening through the center to receive the ball valve in position to control the valve seat outlet of the cup.

6. The combination with an oil supply chamber, an oil chamber forming a seat or 80 support therefor, of a burner and a float approximately in the same horizontal plane with the outlet from the oil supply chamber, whereby the oil level and the oil supply chamber are approximately coincident. 85

7. The combination with an oil chamber having a diaphragm which divides it into two compartments and an oil supply resting upon the chamber with its outlet extending well toward the bottom of the latter, a cup 90 removably resting upon the diaphragm, and extending through an opening in the center thereof, and having a valve seat outlet in its bottom, a float normally in approximately the same horizontal plane from the outlet of 100 the oil supply, the float having an open center into which the cup extends, a ball-valve between the float and cup in position to control the valve-seat opening in the bottom of the latter, and a burner substantially on 105 a level coincident with the outlet of the oil supply and the float.

In testimony whereof I affix my signature.

HENRY M. SHEER.
